EYE PROTECTOR

Donald E. Kimball, Cleveland, Ohio

Application May 27, 1939, Serial No. 276,195

8 Claims. (Cl. 2-14)

This invention relates to eye protectors, more particularly to goggles of the type employed by mechanics, machinists, and others when working with welding torches, abrading wheels, and the like, and has for a principal object the provision of a new and improved adjustable nose-piece construction for goggles.

This application is a continuation in part of my application for Eye protectors, filed August 31, 1938, Serial Number 227,735.

In the drawing accompanying this specification and forming a part of this application, I have shown, for purposes of illustration, embodiments which my invention may assume, and in the drawing:

Figure 1 is a top plan view of an embodiment of the invention, a portion of the head band being broken away to better accommodate the view to the sheet.

Figure 2 is an enlarged, fragmentary, vertical 20 sectional view of the nose-piece construction.

Figure 3 is an enlarged, fragmentary, perspective view of a portion of the eye-cup construction disclosed in Figure 2,

Figure 4 is a view similar to Figure 2, showing 25 another embodiment of the nose-piece holding means,

Figure 5 is a view similar to Figure 2, showing still another embodiment of the invention,

Figure 6 is an enlarged, fragmentary, perspective view of a portion of the eye-cup construction disclosed in Figure 5,

Figure 7 is an enlarged, broken, top face view of a fragment of one of the goggle cups, disclosing yet another embodiment of the invention,

Figure 8 is a fragmentary, vertical sectional view, corresponding substantially to the line 8-8 of Figure 7, while

Figure 9 is a fragmentary, exploded view of another embodiment of the invention.

Referring first to Figures 1 through 3, of the drawing, the eye protectors comprise a pair of eye-cups 10 and 11 of identical construction, except for their opposite disposition. Each of the eye-cups 10 and 11 is preferably molded from a suitable moldable composition, and comprises a substantially circular section 12, circumferentially threaded on the exterior, as at 13, and integrally formed with a rear section 14, the latter being curved to fit the face of the user. The rear section 14 of each of the eye-cups 10 and 11 merges into a temporal portion 15 of greater length than the nose portion, indicated at 16, and is outwardly flared, as at 17, and to the ends of the temporal portions 15, a head band 18 is con- 55

nected, only a fragment of the head band 18 being shown. Threaded onto the threaded section 13, is a bezel 19, having a shoulder 20, against which is adapted to rest, a glass disc 21, a lens proper 22 being adapted to rest against the disc 21, both the disc 21 and lens 22 being adapted to be clamped between the outer edge 23 of the eye-cup and the shoulder 20 of the bezel when the bezel is screwed home.

10 The eye-cups 10 and 11 are secured together by a nose-piece 24, which comprises a chain member 25, covered by a piece of rubber tubing 26, the chain member being made up of a series of spaced balls 27, swiveled onto connecting bars 28, each end of the chain member being adapted to be connected to its related cup at the nose portion 16. For this purpose the nose portion 16 is provided with a slot 29 extending transversely across the edge 30 of the threaded circular section 12, and extending inwardly from the edge 30 a suitable distance, the nose portion 16 being cut out at opposite sides to form substantially half-round, oppositely disposed grooves 31, communicating with the slot 29, the cross-sectional contours of the grooves 31 corresponding substantially to the spherical contour of each of the balls 27 of the chain 25, while the distance between the defining walls of the grooves 31 is the same, or very slightly less than the length of the bars 28, or the distance between adjacent surfaces of the balls 27.

Because of the relative proportions of the balls 27, bars 28, and contours of the grooves 31, when the bezel 19 has been removed, and a bar 28 inserted into the slot 29, and adjacent balls 27 into the grooves 31, the chain is frictionally held in the slot 29 and grooves 31, so that it requires some little force to remove the same. This feature is of advantage in that even with the bezel 19 removed, as when cleaning the lenses, the chain 25 will not readily be disconnected, or the adjustment disturbed, but the chain will remain in place unless forced out of the slot 29 to change the adjustment. Of course when the bezel 19 is screwed on it prevents retraction of the chain 25 from the slot 29 should the chain be subjected to forces sufficient to overcome the frictional resistance already referred to.

40 In Figure 4, all parts of the construction, with the exception of additional parts now to be described, are the same as those shown in Figures 1, 2, and 3, and will be designated by the same reference characters. In this construction, however, instead of at some time relying upon the bezel 19, or solely upon frictional holding when

the bezel is removed, to prevent unintentional detachment of the chain 25, positive lock means 32 are provided, which hold the chain 25 in position at all times independently of the bezel 19 and the frictional holding heretofore mentioned. The lock means preferably take the form of a sleeve 33 having one end split, as at 34, and its opposite end provided with a shoulder 35 and, outwardly of the shoulder 35, with a flat head 36, the sleeve 33 being adapted to be forced into a bore or socket 37, which at right angles intersects the slot 29, the socket 37 preferably opening at the inner side of the nose portion, as shown, to permit insertion and retraction of the sleeve from the inner side of the nose portion.

When the sleeve 33 is in position, by reason of its split nature, it will be held frictionally against accidental retraction, and overlie the chain 25 to prevent its removal from the slot 29 until the sleeve 33 has been removed. The sleeve 33 may readily be removed by inserting the finger nail or some suitable instrument under the flat head 36, and prying the same from the socket 37, thereby releasing the chain 25 for adjusting movement.

In Figures 5 and 6, an embodiment similar to that shown in Figures 1, 2, and 3 is disclosed, and like parts of the two constructions will be indicated by the same reference characters used in connection with Figures 1, 2, and 3. In this embodiment, the section 40 of the nose portion 16, inwardly of the threaded section 41, is of less cross-sectional thickness than the threaded section 41, while the nose portion 16 adjacent the inner extremity of the threaded section 41, is provided with a circumferential rib 42, preferably taking the form of an extension on the innermost thread of the threaded section 41, and which projects radially outwardly beyond the remaining threads 43. The rib 42 is intersected by the grooves 44 and slot 45 similar to the grooves 31 and slot 29 already described in connection with Figures 1, 2, and 3, the grooves 44 preferably being made somewhat deeper than the grooves 31 so that the balls 27 do not fit so tightly.

In this construction, when a bar 28 of the chain member 25 is inserted into the slot 45, the balls 27 somewhat loosely enter the grooves 44, and when the chain is pressed inwardly, the balls 27 encounter the rib 42 and are forced therewith by the application of considerable force, snapping over the same to a position in the bottom portion of the slot 45, and the balls 27 at opposite sides of the section 40, may loosely tilt with respect to the section 40, so that normally there is no tendency for the same unintentionally to pass outwardly of the rib 42. In fact in order to remove the chain member from the slot 45 it is necessary to line up the balls 27 and connecting bar 28 so that they lie substantially at right angles to the opposite side walls of the section 40 and to the defining walls of the grooves 44, before the chain member may readily be snapped outwardly over the rib 42, and the chain member removed for purposes of adjustment. The holding means for the chain member therefore operate independently of the bezel 19 and securely, though detachably, hold the chain member in position when the bezel 19 is removed.

In the embodiment of the invention shown in Figures 7 and 8, many of the parts are similar to those described in connection with Figures 1, 2, and 3, and will be designated by similar reference characters. The nose portion 46 of this construction, however, is made somewhat thicker, preferably being bulged inwardly, as at 47, to

provide additional thickness, and centrally of the edge surface, transversely in line with the bulged portion a socket 48 is provided which extends inwardly a suitable distance, the socket 48 communicating with oppositely disposed transversely extending slots 49. The bottom of the socket 48 is further preferably provided with a threaded recess for the reception of a threaded stud 50, formed on the bottom of a cup 51, inserted into the socket 48, the cup being slightly reduced in diameter toward its outer end as at 52, and extending outwardly to a point substantially flush with the entrance to the socket 48, the reduced portion 52 being split at opposite sides, as at 53, in line with the slots 49, the cup 51 being constructed of springy metal so that the splits 53 normally are sprung substantially closed. In this construction, a ball 27 is adapted to enter the cup 51, the bars 28 being pressed into the splits 53, and passed through the slots 49, the split reduced section frictionally holding the bars 28, and the ball 27, and of course the chain member 25, against unintentional retraction, when the bezel 19 is not in position.

In Figure 9, there is disclosed an embodiment of the invention operable to provide a continuous surface along the edge of the eye-cup, even though holding means of the character heretofore set forth are employed. The nose-portion 16 is provided with grooves 54 and a connecting slot 55 as before described, but in this case the outer edge of the eye-cup is cut out, as at 56, for the reception of a plug or cover member 57, having a flat body portion 58 shaped to fit flush into the recess 56, and having curved spring prongs 59 adapted to fit into the grooves 54 and frictionally hold the cover member in position, the cover member of course acting as a locking member to hold the chain member in position when the bezel is removed, but being detachable to permit adjustments to be made.

It will be apparent to those skilled in the art that I have accomplished at least the principal object of my invention, and it also will be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

I claim:

1. Eye protecting fastening means, comprising: a pair of eye protecting means; nose bridge means for flexibly connecting the eye protecting means together; at least one of said protecting means being in the form of a cup-shaped member having a slot therein for the reception of said nose bridge means, said member between the ends of said slot and for a relatively short distance therealong being provided with an enlargement, said nose bridge means having abutments and connecting links between said abutments, said links each being spaced apart a distance slightly less than the lateral thickness of said member at said enlargement, whereby movement of one of said links past said enlargement necessitates forcing said spaced abutments therepast to hold the nose bridge means against accidental detachment.

2. Eye protecting fastening means, comprising: a pair of eye protecting means; nose bridge means for flexibly connecting the eye protecting means together; at least one of said protecting

means being in the form of a cup-shaped member having a thread thereon, and having a slot therein for the reception of said nose bridge means, said member between the ends of said slot and for a relatively short distance therealong being provided with an enlargement formed by a portion of said thread; said nose bridge means having abutments and connecting links between said abutments, and said links each being spaced apart a distance slightly less than the lateral thickness of said member at said enlargement, whereby movement of one of said links past said enlargement necessitates forcing said spaced abutments therepast to hold the nose bridge means against accidental detachment.

3. Eye protector fastening means, comprising in combination with a pair of eye protecting means, nose bridge means for flexibly connecting said eye protecting means, said nose bridge means including ball means spaced apart a predetermined distance, and link means between said ball means; at least one of said eye protecting means being in the form of a cup-shaped member having a tubular part for the threaded reception of a lens holding bezel, the wall of said tubular part in cross-sectional thickness being substantially greater than the distance between said ball means, and having a recess for the adjustable reception of said nose bridge means, said recess opening through the outer edge of said tubular part, and extending inwardly from said edge, the walls of said tubular part at opposite sides of said recess being cut out to form grooves communicating with said recess, said grooves being oppositely disposed and substantially half-round in cross-section, and adapted to provide room for spaced adjacent balls and to permit entry of the connecting link between said balls into said recess.

4. Eye protector fastening means, comprising in combination with a pair of eye protecting means, nose bridge means for flexibly connecting said eye protecting means, said nose bridge means including ball means spaced apart a predetermined distance, and link means between said ball means; at least one of said eye protecting means being in the form of a cup-shaped member having a tubular section for the threaded reception of a lens holding bezel, the wall of said tubular part in cross-sectional thickness being substantially greater than the distance between said ball means and having an external thread molded thereon for threaded reception of said bezel, said molded thread terminating short of the opposite end of said tubular part, the latter having a recess for the adjustable reception of said nose bridge means, said recess opening through the outer edge of said tubular section, and extending inwardly from said edge and past the threaded portion, the walls of said tubular part at opposite sides of said recess being cut out to form grooves interrupting said molded thread and communicating with said recess, said grooves being oppositely disposed and substantially half-round in cross-section, said recess and said grooves terminating inwardly of said threaded portion, said grooves being adapted to provide room for spaced adjacent balls and to permit entry of the connecting link between said balls into said recess.

5. Eye protective fastening means, comprising in combination with a pair of eye protecting means, nose bridge means for flexibly connecting the eye protecting means together, including spaced abutments with connecting means there-

between, at least one of said protecting means being in tubular form having an outer end portion somewhat thicker in cross-section than an adjacent inner portion thereof, said outer portion having a recess extending therethrough and into said inner portion, for the detachable reception of the connecting means of said bridge means, the opposed walls defining said outer portion being spaced apart substantially the normal maximum distance between said abutments, whereby to operably enter and leave said recess the abutments and connecting means of said bridge means must lie in a plane substantially at right angles to said opposed walls, being loosely shiftable in the recess of said inner portion, and non-removable from said inner portion recess until lined up substantially at right angles to the said opposed walls of said outer portion.

6. Eye protective fastening means, comprising in combination with a pair of eye protecting means, nose bridge means for flexibly connecting the eye protecting means together, including spaced abutments with connecting means therebetween, at least one of said protecting means being in tubular form having an outer end portion somewhat thicker in cross-section than an adjacent inner portion thereof, said outer portion having a recess extending therethrough and a continuation of said recess extending into said inner portion, said recess and continuation being adapted to have the connecting means of said bridge means enter through said recess and enter the continuation thereof; the opposed walls defining the recess of said outer portion being spaced apart substantially the normal maximum distance between said abutments except for a relatively short distance between the ends of the recess and continuation having at this point an enlargement slightly greater than the distance between the abutments of said nose bridge means, while the walls defining the continuation of said recess are spaced a less distance apart, said nose bridge means being loosely shiftable when in the continuation of said recess, and non-removable from said continuation until lined up substantially at right angles to the opposed walls of the recess of said outer portion and forced past said enlargement.

7. Eye protector fastening means, comprising; a pair of eye protecting means; nose bridge means for connecting said eye protecting means, said nose bridge means including spaced ball means, and link means between said ball means: at least one of said eye protecting means being in the form of a cup-shaped member having a tubular section for the threaded reception of a lens holding bezel, and a lens holding bezel detachably engageable with said tubular section; said tubular section having a recess for the adjustable reception of said nose bridge means, said recess opening through the outer edge of said tubular section, and extending inwardly from said edge, the defining walls of said recess and said nose bridge means being constructed and proportioned to interengage snugly, and thereby effect frictional resistance to accidental disconnection of said nose bridge means when said lens holding bezel is removed from said tubular section; and detachable locking means for preventing removal should said friction holding means be accidentally overcome.

8. Eye protector fastening means, comprising in combination with a pair of eye protecting means, nose bridge means for flexibly connecting said eye protecting means, said nose bridge

means including ball means spaced apart a predetermined distance, and link means between said ball means; at least one of said eye protecting means being in the form of a cup-shaped member of moldable material having a tubular part for the threaded reception of a lens holding bezel, the defining wall of said tubular part being integrally formed, and having a cross-sectional thickness substantially in excess of the distance between said ball means, and having a recess 10

for the adjustable reception of said nose bridge means, said recess opening through the outer edge of said tubular part and extending inwardly from said edge, the wall of said tubular part 5 along said recess being reduced to provide room and direct support for spaced adjacent balls of said nose bridge means, and for entry of a connecting link means into said recess.

DONALD E. KIMBALL.
